UNITED STATES PATENT OFFICE.

HUMPHREY FRANCIS PARKER, OF DUNEDIN, NEW ZEALAND.

AEROPLANE AND THE LIKE.

1,312,571.

Specification of Letters Patent.

Patented Aug. 12, 1919.

Application filed April 2, 1918. Serial No. 226,258.

To all whom it may concern:

Be it known that I, HUMPHREY FRANCIS PARKER, a citizen of the Dominion of New Zealand, and residing at Dunedin, in the 5 Provincial District of Otago, in the Dominion of New Zealand, have invented certain new and useful Improvements in Aeroplanes and the like, of which the following is a specification.

- 10 This invention relates to aeroplanes and other similar flying machines, and the object of the invention is to provide means whereby the speed of range of aeroplanes is increased, so that in aeroplanes designed to have the 15 same maximum speed, lower speeds are obtainable for taking off and alighting, than is possible with machines heretofore constructed, and in aeroplanes designed to have the same minimum speed, higher maximum 20 speeds are obtainable than heretofore; and whereby control may be exercised over the travel of the center of pressure, rendering it possible to maintain the center of pressure in an approximately stationary position, 25 thereby securing neutral longitudinal equilibrium, or to bring about a reversal of the direction of the travel of the center of pressure, thereby securing stable longitudinal equilibrium in the wings themselves. 30 The above objects are attained by the use with an ordinary main plane or planes of one or more auxiliary planes or sets of planes arranged symmetrically and the first object is attained by varying the angle of incidence of such plane or planes relatively to the main plane or planes and at the same 35 time altering their shape, and the second object is attained by setting the auxiliary plane or planes in a more backward position than 40 the main plane or planes, as hereinafter described.

The invention as applied to an aeroplane with a single main plane between two auxiliary planes is illustrated in the accompanying drawings, wherein:—

Figure 1, is a diagrammatic sectional elevation of a set of planes adjusted for maximum speed,

Fig. 2, is a diagrammatic sectional elevation of a set of planes adjusted for taking off or landing,

Fig. 3, is a diagrammatic side elevation of the rib of an auxiliary plane,

Fig. 4, is a side elevation of an auxiliary 55 rib, in its lifting position,

Fig. 5, is a side elevation of an auxiliary rib in its non lifting or streamline position,

Fig. 6, is a front elevation, and

Fig. 7, is a side elevation of a link and its connections,

Fig. 8, is a longitudinal sectional elevation of a fastener.

Fig. 9, is a cross section of shallow channel steel.

The main plane, see Figs. 1 and 2, is of ordinary construction and auxiliary planes 2 and 3 are provided. In the drawings the plane 2 is shown above, and the plane 3 is shown below, the main plane 1. The auxiliary planes 2 and 3 are preferably of the same length and width as the main plane 1 but it will, of course, be understood that the auxiliary planes may be made smaller or larger than the main plane if desired.

In level flight at maximum speed the auxiliary planes are to be set to lie along the direction of the air flow, so that they do not contribute to the lift of the machine, as shown in Fig. 1, the area of the main plane 1 being such that its lift supports the machine at the angle of incidence giving the greatest ratio of lift to drag for the type of wing employed. The main plane 1 Fig. 1, is shown set to fly at this angle, approximately three degrees.

When the main plane 1 is set at its maximum incidence, see Fig. 2, as when landing the auxiliary planes 2 and 3 contribute their maximum lift, that is to say, the main plane and auxiliary planes are set at about fifteen degrees to the direction of the air flow. The additional incidence thus given to the auxiliary planes is obtained by causing the trailing edges to move downward, as hereinafter described.

The auxiliary planes 2 and 3 are to have a low value for the drag in their non lifting position, and a high value for their lift at the angle of maximum incidence. To comply with these conditions it is necessary, when altering the incidence of the planes, also to alter their shape, so that in the non lifting position they have a pure "streamline" form, and at their maximum incidence the form of a high lift wing.

The pure "streamline" form is shown by full lines in Fig. 3, and the "high lift" form is shown by dotted lines in the same figure. By "pure streamline" form, I mean a plane having its upper surface curved upwardly

from a line passing through the front and rear edges of the plane, and its lower surface curved downwardly the same distance from said line. By "high lift" form, I mean a 5 plane having both its upper and lower surfaces curved upwardly.

The ribs of the auxiliary planes 2 and 3, see Figs. 1, 2, 4, and 5, each comprises a frame 6 of spring steel. The thickness of 10 the steel and its rigidity are determined by the curvature which the frame may be required to take, and the section of the steel may be rectangular, or the edges of the steel may have small flanges to form a shallow 15 channel, see Fig. 9, to give greater rigidity where required. The nose of the frame 6 is attached to the front spar 4. The upper portion of the frame is secured to the rear spar 5, by a bracket 24.

20 The lower portion of the said frame 6 is connected to the upper portion thereof by links 7 and a slide 8. The links 7 are connected by pins 9 to brackets 10 and 11 fixed to the upper and lower portions respectively 25 of the frame 6. The slide 8 is fixed to the rear upper portion of the frame 6 and comprises a bar 14 parallel to the lower portion of the frame 6. The length of the bar 14 is equal to the distance the upper portion 30 of the frame 6 travels forward over the lower portion thereof when the plane changes from its "streamline" to its lifting shape. Flanges or lugs 13 upon the lower portion of the frame 6 carry a pin 12 which 35 slides upon the top of the bar 14, thereby allowing the necessary motion. Longitudinal angle or other shaped bars 16, 17, 18, and 19 are provided for stiffening the plane.

The front spars 4 of the auxiliary planes 40 2 and 3 are located near to the leading edge of the said planes and are capable of partial rotation about their axes, and for this purpose are mounted in bearing brackets 44 in the front struts 22. The rear spars 45 5 are mounted in slots 20 formed in brackets 45 carried by the rear struts 21. The length of the slot is determined by the distance the rear spar is to move forward when the plane changes from the "streamline" to the 50 lifting shape. The position of the forward end of the slot, against which the rear spar bears, see Fig. 2, determines the amount of camber given to the plane, the camber being greater as the movement forward of the rear spar is greater, and less as the movement forward is less.

Compression bars A and B are connected to the brackets 44 and 45 for keeping the struts 21 and 22 in spaced relation.

60 A separate central control is not necessary, the operation of the planes being automatic. When the pilot pulls the central control lever back the attitude of the machine is changed and the auxiliary planes 2 and 3, instead of lying along the direction of the

air flow, are set at an angle to the said flow. The air pressure thus brought into play acts against the auxiliary planes and causes the planes to change to the desired shape. The air pressure on the portion of the plane 70 between the front spar 4 and the rear spar 5 being greater than the air pressure on the portion between the rear spar and the trailing edge 25, the portion between the front and rear spars is compelled to move upward 75 and the trailing edge in consequence is constrained to move downward. The correct amount of movement is that which sets the chord of the auxiliary plane, see Fig. 2, at an angle to the line through the centers of the front and rear spars equal to the incidence given to the main plane 1 in Fig. 1. When the pilot wishes to fly the machine at maximum speed again, and alters the elevator accordingly, the auxiliary planes are once more brought to lie along the direction of the air flow. The action of the frames 6 then causes the same to return to their "streamline" shape. 90

In a modification, control cables 30 and 31 are attached to the steel frame 6 of the auxiliary planes at the points 26 and 27, the cable 30 being attached to the upper surface of the ring 3 and to the lower surface of the wing 2, and the cable 31 being attached to the upper surface of the plane 2 led over pulleys 32 to the lower surface of the plane 3. The auxiliary planes on the right of the body of the machine are similarly connected with the planes on the left thereof. In the event of an obstruction preventing any one of the planes from assuming its proper shape the other planes of the series are also prevented from assuming that 95 shape until the air pressure on those planes, through the medium of the cables, has been exerted to bring the obstructed plane into its correct position. On the obstruction being overcome all the planes assume their 100 correct shape, or should the pressure thus brought to bear be insufficient to overcome the said obstruction, no change takes place in any of the wings. 105

The auxiliary planes 2 and 3 are set back 115 relatively to the main plane 1 for a distance 23 shown by dotted lines in Figs. 1 and 2.

The setting back of the auxiliary planes 2 and 3 relatively to the main plane 1 is such that the moment of the lift they contribute about the maximum speed position of the center of pressure of the main plane, balances the moment due to the movement forward of the center of pressure of the main plane as the incidence is increased up 120 to the maximum.

In the above mentioned maximum speed position of the center of pressure there is no moment to balance and as stated no lift on the auxiliary planes. But when the 130

angle is altered a moment comes into existence due to the travel of the center of pressure of the main plane. Simultaneously the auxiliary planes start to take lift and 5 thus to provide a correcting moment.

By reducing the set back for the auxiliary planes 2 and 3, the upsetting moment due to the travel of the center of pressure may be merely reduced, and by increasing the set 10 back a stabilizing moment is introduced which increases directly as the set back increases.

What I do claim and desire to secure by Letters Patent of the United States is:—
15 1. In an aeroplane, the combination with a rigid main plane, of an auxiliary plane having a flexible frame of pure stream-line shape adapted upon increase of the angle of incidence of the planes relative to the direction of air flow, to flex, under the pressure 20 of said air flow, from said stream-line shape to a lift shape.

2. In an aeroplane, the combination with a rigid main plane of an auxiliary plane 25 having a flexible frame normally assuming a pure stream-line shape, said auxiliary plane being so mounted on the frame of the machine as to be capable upon increase of the angle of incidence of the planes relative to 30 the direction of air flow, to flex, under the pressure of said air flow, from said stream-line shape to a lift shape.

3. In an aeroplane, a frame, a rigid main-lifting plane, and an auxiliary plane 35 mounted on the frame and normally having a non-lifting shape in cross-section, said auxiliary plane being so constructed and connected to the frame as to be capable upon increase of the angle of incidence of the 40 plane relative to the direction of air flow, to flex, under the pressure of said air flow, from said stream-line shape to a lift shape.

4. In an aeroplane, a frame, a main lifting plane, a front spar connected to the 45 frame and capable of partial rotation, an auxiliary plane having a flexible frame secured to said spar, and means for securing the rear portion of the flexible frame to the frame of the machine.

50 5. In an aeroplane, a frame, a main lifting plane, a front spar pivotally connected to the frame, a rear spar carried by the frame and movable toward and away from the front spar, an auxiliary plane having a 55 flexible frame of approximately elliptical shape, the front portion of the top and bottom parts of the flexible frame being secured to the front spar, and means connecting the rear portion of the top part of the flexible 60 frame to said rear spar.

6. In an aeroplane, a fixed main plane, an auxiliary plane having ribs made with frames of spring steel, a front spar attached to the upper and lower portions of the 65 frames and partially rotatable, front struts

having bearings for the spar, a rear spar to which the ribs are attached and rear struts having horizontal slots in which the rear spar is slidably mounted.

7. In an aeroplane, a fixed lifting plane, 70 and an auxiliary plane having ribs of sufficient rigidity to keep the auxiliary plane in streamline shape when set in the direction of the air flow, said ribs being constructed to yield when set at an angle to the air flow, to 75 change the auxiliary plane to a lifting shape.

8. In an aeroplane, a fixed main plane, and flexible auxiliary planes arranged above and below the main plane, said auxiliary planes upon increase of the angle of incidence of the planes relative to the direction of air flow being adapted to automatically assume angles different relatively to the angle of the main plane. 80

9. In an aeroplane, a main lifting plane, 85 and a flexible auxiliary plane adapted at large angles of incidence to carry a substantial part of the weight of the machine, said auxiliary plane being rearwardly spaced with respect to said main plane, whereby 90 the shifting of the load to said auxiliary plane with increase in incidence angle maintains the center of lift of said planes taken as a whole in a substantially constant position. 95

10. In an aeroplane, a main lifting plane, and flexible auxiliary planes adapted at large angles of incidence to carry a substantial part of the weight of the machine, one 100 of said auxiliary planes being upwardly and rearwardly spaced with respect to said main plane and the other of said auxiliary planes being downwardly and rearwardly spaced with respect to said main plane, whereby the shifting of the load to said auxiliary 105 planes with increase in angle of incidence, maintains the center of lift of said planes as a whole in a substantially constant position.

11. In an aeroplane, a frame, a main lifting plane, and an auxiliary lifting plane having a front spar, a rear spar and ribs of sufficient rigidity to maintain the auxiliary plane in stream-line shape when set in the direction of air flow, said ribs consisting of a front portion capable of limited rotary motion about the axis of the front spar, a middle portion of flexible construction capable of deforming upward when set at an angle to the air flow, and a rear portion capable of limited rotary motion about the axis of the rear spar and a limited horizontal sliding motion relative to the frame. 110 115

12. In an aeroplane, a frame, a main lifting plane connected to the frame, spars carried by the frame, ribs of flexible material secured to the spars and having a normal stream-line shape, and plane fabric covering said ribs and forming therewith an auxiliary plane capable upon increase of the 120 125 130

- angle of incidence of the planes relative to the direction of air flow, to flex under the pressure of said air flow, from a streamline shape to a lift shape.
- 5 13. In an aeroplane, a main plane, an auxiliary plane having ribs of flexible material for supporting the plane fabric; said ribs having a normal "streamline" shape; a rotatable front spar; a laterally slidable rear 10 spar; and means connecting said ribs with said spars; said ribs and the fabric supported thereby being adapted, upon increase of the angle of incidence of the planes relative to the direction of air flow, to flex, under the pressure of said air flow, from said "streamline" shape to a maximum lift 15 shape.
14. In an aeroplane, a main plane, an auxiliary plane including a rib structure for 20 supporting the plane fabric, comprising upper and lower flexible members joined together at their forward ends, means interconnecting the tail ends of said members so as to permit of a limited longitudinal 25 movement thereof relative to each other, links articulately interconnecting said upper and lower rib members, said ribs having a normal "streamline" shape; spars for supporting said ribs; and said ribs together 30 with the fabric supported thereby being adapted, upon increase of the angle of incidence of the planes relative to the direction of air flow, to flex, under the pressure of said air flow, from said "streamline" 35 shape to a maximum lift shape.
15. In an aeroplane, a main plane, an auxiliary plane including a rib structure for supporting the plane fabric comprising upper and lower flexible members joined to- 40 45 50 55 60 65 70
- gether at their forward ends, means interconnecting the tail ends of said members so as to permit of a limited longitudinal movement thereof relative to each other, links articulately interconnecting said upper and lower rib members, said ribs having a normal "streamline" shape; a front spar; a rear spar; forward struts; rear struts; means for rotatably mounting said front spar in connection with said forward struts; means slidably mounting said rear spar for lateral movement in connection with said rear struts; means for securing the forward ends of said upper and lower rib members to said front spar; and means for securing said upper rib member, intermediate of its forward and tail end to said rear spar.
16. In an aeroplane, a frame, a main lifting plane, an auxiliary lifting plane having a front spar, a rear spar and ribs of sufficient rigidity to maintain the auxiliary plane in streamline shape when set in the direction of air flow, said ribs being so constructed that the portion between the front and rear spars is capable of deforming upwardly when set at an angle to the air flow while the portion to the rear of the rear spar is capable of limited rotary motion about the axis of the rear spar, and means permitting a limited horizontal sliding movement of the rear portions of the ribs.

In testimony whereof I have signed my name to this specification in the presence of two witnesses.

HUMPHREY FRANCIS PARKER.
